United States Patent Office

Des. 229,499

Patented Dec. 4, 1973

229,499

BATTERY CHARGER OR SIMILAR ARTICLE

Donald K. Krumin and Richard J. Toth, Fort Lauderdale,
Fla., assignors to Motorola, Inc., Franklin Park, Ill.

Filed Oct. 13, 1971, Ser. No. 188,631

Term of patent 14 years

Int. Cl. D13—02

U.S. Cl. D26—15 B

FIG. 3

FIG. 4

FIG. 5

FIG. 1 is a front perspective view of a battery charger or similar article showing our new design;

FIG. 2 is a rear elevation thereof;

FIG. 3 is a top plan view thereof;

FIG. 4 is a side elevation thereof;

FIG. 5 is a bottom plan view thereof.

The side opposite FIG. 4 is a mirror image of the side shown.

We claim:

The ornamental design for a battery charger or similar article, substantially as shown and described.
